HINGE CONSTRUCTION

Arthur G. Lyons, Pennside, Pa., assignor to Reading Hardware Corporation, Reading, Pa., a corporation

Application March 27, 1933, Serial No. 663,016

5 Claims. (Cl. 16—136)

This invention relates to improvements in anti-friction hinge constructions.

The primary object of this invention is the provision of improved anti-friction devices for butt hinges and the like, which is relatively simple, durable, and may be handled with facility without loss of the parts thereof. Furthermore, the anti-friction device embodies improved means for mounting the same upon a hinge knuckle, so that should the bearing not operate properly, wear incident to support of a load will be imparted to a wear resisting portion.

Other objects and advantages of this invention will be apparent during the course of the following detailed description.

In the accompanying drawing, forming a part of this specification, and wherein similar reference characters designate corresponding parts throughout the several views,

20 Figure 1 is an elevation of a hinge showing the complementary leaf and knuckle parts and associated anti-friction devices.

25 Figure 2 is a vertical sectional view taken along the pintle axis of the improved hinge structure substantially upon the line 2—2 of Figure 1.

20 Figure 3 is a side elevation of one of the improved anti-friction devices.

30 Figure 4 is a vertical sectional view taken through the anti-friction device of Figure 3 substantially on the line 4—4 of Figure 3.

35 Figure 5 is a transverse sectional view taken through an anti-friction bearing portion of the improved device.

35 Figure 6 is a sectional view taken through a sleeve or bushing which is adapted to be slipped through the bearing of Figure 5 and riveted or otherwise assembled thereto to provide the anti-friction unit of Figures 3 and 4.

40 Figure 7 is a perspective view of one leaf of the hinge, showing how the central knuckle is counterbored or recessed to receive the bearing bushing.

45 In the drawing, wherein for the purpose of illustration is shown only a preferred embodiment of the invention, the letter A may generally designate the improved hinge construction, which may consist of complementary leaf portions B and C, a pintle D, and anti-friction devices E.

50 The hinge section B consists of the leaf 10 and barrel or knuckle portions 11 and 12. The hinge section C consists of the leaf 13 and the barrel or knuckle portions 14, 15 and 16. Of course all of the knuckle portions are provided with axial passageways 17 adapted to be aligned, since the 55 knuckle portions of the hinge sections are inter-

fitting and complementary; these passageways being adapted to receive the shank of the spindle D in the usual manner. While the drawing shows a hinge with only one of the knuckles provided with anti-friction devices attached thereto it is within the contemplation of this invention to have similar anti-friction devices attached to any or all of the knuckles on one or both ends of the same. As shown in the drawing the hinge A has the knuckle 15 provided at each end with anti-friction devices E. To accommodate the anti-friction devices, the passageways at each end of the knuckle 15 are counter-bored at 20, as shown in Figure 2.

Referring to the improved anti-friction device 15 E, the same includes a bearing assemblage 25, shown in Figure 5, and an attaching bushing 26, shown in Figure 6, both of which are assembled to provide the anti-friction unit E.

Referring to the bearing construction 25 the same comprises a pair of races or washers 27 and 28 which are grooved in complementary relation to receive ball bearings or similar anti-friction elements 29. These races or washers are of ring-shaped formation, having aligning passageways 30 therethrough adapted to freely receive the sleeve or bushing 26. At their outer faces the races are counter-bored or recessed annularly at 31. It is noted that the outer peripheries of the races are convexly arcuated or beveled, and over these peripheral surfaces is spun or otherwise disposed a thin sheet metal housing 35, which may be of some soft material, such as brass, in contradistinction to the races 27 and 28. This housing 35 acts as a protective covering for the 30 races and the ball bearings and permanently holds the races and ball bearings assembled. It is annularly flanged at 37 over the outer side of one of the races, such as the race 27, but is not flanged over the outer face of the other race, as 40 will be noted from Figure 5. This housing, as is conventional, does not restrict relative rotation of the races 27 and 28, although it does hold all of the parts assembled.

The bushing 26, which is of sleeve-like construction, is preferably of steel or some other material which is wear resisting. It includes the cylindrical portion 40 and a thicker cylindrical attaching portion 41 provided with an annular wear resisting shoulder 42 at the juncture with 50 the portion 40. A passageway 43 is of course provided through the bushing 26, within which the pintle D may be slipped. The outer end of the portion 40 may be beveled as shown at 44 in Figure 6. The body 40 of the bushing 26 is slipped 55

through the passageway 30 of the bearing portion 25 and the beveled end of the portion 40 is suitably peened or riveted in the counter-bored or recessed portion 31 of one of the races 27, as shown at 45 in Figure 4 of the drawing. In this manner the bearing portion 25 of the anti-friction unit is rotatably assembled upon the sleeve portion 40 with a slight longitudinal movement between the flange 45 and the shoulder 42. Of course the race 28 rests upon the wear resisting shoulder 42, as is well shown in Figure 4. It is to be noted that the flange portion 45 does not project beyond the housing flange 37.

In the assemblage of parts the portion 41 of the bushing is driven into the socket or counterbore 20 of the knuckle 15. When it is entirely in place the shoulder 42 is about positioned flush with the end surface of the knuckle 15, although it may lie slightly beyond the outer end surface of the knuckle, so that should the bearing not operate properly, as when the race way becomes clogged with dirt, or the ball becomes broken, or the butts be placed on the door out of alignment, causing relative rotation to take place between the facing surfaces of the race and shoulder 42, the major support will be placed upon the wear resisting shoulder 42 and with little tendency to wear away the knuckle.

I am well aware that it has heretofore been proposed to use bearings of the general character shown in my invention. However, it has not heretofore been proposed to use an attaching bushing or sleeve in a compact unitary assemblage with the bearing portion of the anti-friction device in such relation that there will be small likelihood of loss of any of the parts while independent of attachment to the hinge. Furthermore, it is a very important characteristic that the wear is taken upon a wear resisting portion of the unit and not upon the end of the knuckle to which the unit is attached. This enables a more efficient working hinge wherein the tolerances are practically uniform, so that there is small likelihood of sagging of the load, due to wear upon the hinge parts, and practically no maintenance in order to assure efficient operation is negligible.

Various changes in the shape, size, and arrangement of parts may be made to the form of invention herein shown and described, without departing from the spirit of the invention.

I claim:

1. In a hinge the combination with separate leaves having pintle receiving knuckles and a connecting pintle passed therethrough, an anti-friction device interposed between the adjacent ends of knuckles of the opposed leaves and including races and an anti-friction element therebetween, and a wear-resisting member of better wear resisting material than the knuckle non-rotatably anchored in concealed relation within the end of a knuckle where the strain is received and having a race of the bearing resting thereupon.

2. In a hinge section the combination of a knuckle having a pintle receiving passageway

therethrough and a counterbore at an end thereof, a bushing sleeve seated in said counterbore having a reduced sleeve-like extension projecting beyond the adjacent end of the knuckle, said bushing at the adjacent end of the knuckle having a wear resisting shoulder lying substantially flush with said adjacent end, and an anti-friction bearing rotatably attached to and mounted upon the extension of said bushing which projects from the knuckle and having a race in seating engagement upon said wear resisting shoulder.

3. In a hinge section the combination of a knuckle having a pintle receiving passageway therethrough, a bushing sleeve anchored in said pintle receiving passageway and having a reduced sleeve-like extension projecting beyond an end of the knuckle, said bushing at the end of the knuckle from which said extension projects having an annular shoulder lying substantially flush with the adjacent end of the knuckle, and an anti-friction bearing rotatably attached to and mounted upon said reduced extension of the bushing including a pair of races with anti-friction bearing members disposed therebetween, one of said races resting directly upon said annular shoulder and the other having the extreme end of said extension of the bushing overturned thereupon to prevent removal of the anti-friction device from said extension.

4. In a hinge section the combination of a knuckle having a pintle receiving passageway therethrough and a counterbore at an end thereof, a bushing sleeve including a thickened body portion anchored in said counterbore and a reduced sleeve-like extension projecting therefrom beyond the adjacent end of the knuckle, said bushing having a passageway therethrough of substantially uniform diameter and providing at the juncture of the body with said extension an annular shoulder lying substantially flush with the adjacent end of the knuckle, and an anti-friction device rotatably mounted upon the said extension of the bushing including a pair of races with ball bearings therebetween, one of the races resting on said shoulder and the extreme end of the extension of the bushing being overpeened upon the other race to prevent longitudinal detachment of the anti-friction device from said bushing.

5. A hinge comprising leaves with co-acting knuckles, a pin removably mounted in said knuckles for connecting the leaves, an anti-friction unit between the facing surfaces of the knuckles of the leaves, and a wear resisting member non-rotatably anchored upon the knuckle which receives the strain incident to support of a load, having the anti-friction unit resting thereon whereby to receive wear incident to relative rotation between the anti-friction unit and said wear resisting member, said wear resisting member being of metal more resistant to wear than the material of the knuckle.

ARTHUR G. LYONS.
